CLAIM

The ornamental design for an ice bag holder, as shown and described.

DESCRIPTION

FIG. 1 is a side elevational view of an ice bag holder showing our new design, the broken line showing of the head is for illustrative purposes only and forms no part of the claimed design;

FIG. 2 is a rear perspective view thereof;

FIG. 3 is a front perspective view thereof with the strap disconnected;

FIG. 4 is a top plan view of the holder in open position;

FIG. 5 is a bottom plan view of the holder in open position.

FIG-1

FIG-5

UNITED STATES PATENT AND TRADEMARK OFFICE
CERTIFICATE OF CORRECTION

PATENT NO. : Des. 290,512

DATED : June 23, 1987

INVENTOR(S) : Babb et al

It is certified that error appears in the above-identified patent and that said Letters Patent is hereby corrected as shown below:

On the title page, at the top and in item [76], "Bagg et al" and "Daisy B. Bagg" are incorrect and should read -- Babb et al -- and -- Daisy B. Babb --, respectively.

Signed and Sealed this
Thirteenth Day of October, 1987

Attest:

DONALD J. QUIGG

Attesting Officer

Commissioner of Patents and Trademarks
